UNITED STATES PATENT OFFICE.

ARCHIBALD R. THOMPSON, OF LAKewood, OHIO.

BURNER.

1,273,423.

Specification of Letters Patent. Patented July 23, 1918.

Application filed December 15, 1915. Serial No. 66,887.

To all whom it may concern:

Be it known that I, ARCHIBALD R. THOMPSON, a citizen of the United States, residing at Lakewood, in the county of Cuyahoga and State of Ohio, have invented a certain new and useful Improvement in Burners, of which the following is a full, clear, and exact description, reference being had to the accompanying drawings.

10 This invention relates to burners that are adapted for use with either gaseous or liquid fuel, and when used in these respective connections act as regenerative gas burners or as vaporizing liquid fuel burners.

15 The invention has for its objects to provide a burner of the aforesaid character that is simple of construction; economical of production; convenient of use; that is safe; and that is practically odorless, the principle on 20 which the burner operates insuring a more perfect combustion than prevails in the usual gas or liquid fuel burners, thereby obviating the unpleasant and injurious fumes incident to the use of burners of the aforesaid usual character.

25 A further object of the invention is to provide a burner of the sort above described that is extremely efficient and which effects a material saving of fuel when used either 30 as a liquid fuel or gas burner. When acting as a regenerative gas burner, the gas is passed through a chamber wherein it is subjected to the heat from the burner proper, causing an expansion of the gas, and combustion of the carbon therein, thus producing 35 a highly combustible gas which burns with a very high degree of heat, the chemical composition of the gas being actually changed by this treatment, as will be understood by those familiar with the subject.

40 When used as a liquid fuel burner, the fuel is passed through the aforesaid chamber and under the influence of the heat from the burner, is converted into a highly inflammable gas or vapor, so that when it issues 45 from the burner it burns with an intense heat and with the consumption of but a minimum amount of fuel.

50 A still further object of my invention is to provide a burner of the foregoing character within which is incorporated a grid, preferably the burner and grid being formed of an integral casting.

55 The foregoing objects, and others which will become apparent as this description proceeds, are attained in a burner construct-

ed in accordance with the accompanying drawing, and while I will proceed to describe the same in detail, I wish to be understood as not limiting myself to the structural 60 details thereof further than is required by the terms of the annexed claims and is rendered necessary by the state of the prior art.

In the drawings, Figure 1 is a perspective view of the burner; Fig. 2 is a central vertical section through the burner, on the line 2—2 of Fig. 3; Fig. 3 is a similar view on line 3—3 of Fig. 2, this and the former view being taken at right angles to each other; Fig. 4 is a bottom plan view of the burner; 70 and Fig. 5 is a top plan view of a modified form of the invention.

The burner is preferably composed of an integral casting comprising a fuel diffusing and preheating chamber 1 and a burner 75 chamber 2 that are connected by a wall 3, and between which communication is established through a conduit 4, a wall 5 extending downward from the burner chamber to provide an air inlet passageway, the admission of air to such passageway being controlled by a shutter 6 having openings 7 which are adapted to coöperate with openings 9 in the circular bottom 10 of the burner, said shutter being rotatably connected to the burner bottom by a center bolt 11.

The burner shown herein is circular in plan, wherefore the preheating chamber 1 and the burner chamber 2 are annular and 90 the wall 3 is frusto conical, the frusto conical shape of the wall 3 resulting from the preheating chamber being somewhat larger than the burner chamber, and from the fact that the outer sides of both are connected by 95 said wall. To increase the capacity of the preheating chamber, and also to provide a portion of it that is more effectively located with respect to the source of heat than the above mentioned annular portion, I provide 100 a conduit 15 which extends diametrically across the preheating chamber and which terminates at one end adjacent the aforesaid conduit 4, the opposite end being substantially in alinement with a threaded extension 16, for the application of a suitable supply connection, such being shown herein as a valve 17 which controls the supply of fuel from the pipe 18 to the burner. It follows, from the general shape of the burner, 110 that the wall 5 is cylindrical, and that the shutter 6 is circular, the latter being pro-

105

110

vided with an upwardly extending peripheral flange 19 which fits about the bottom of the burner and which may be knurled, if desired, to facilitate turning or adjusting 5 the shutter.

The upper side of the burner chamber 2 (and it will be observed from Figs. 2 and 3 that this chamber is substantially circular in cross section) is provided with three series 10 of apertures, the apertures of each series being arranged in a circle. The apertures of all of the series radiate substantially from the center of the cross section of the burner chamber, and those of the inner series 15 converge along lines which practically meet at the center of the conduit 15, while those of the outer series diverge along lines substantially parallel to the wall 3 and strike beneath the annular portion of the preheating chamber 1, the apertures of the central 20 series extending substantially vertically through the wall of the burner chamber. Formed about the inner side of the burner chamber, just below the inner series of apertures, is a rib 25 which extends inward and 25 upward from said chamber to the level of the top thereof, or higher, if desired, and produces an annular trough 26.

For reasons of convenience and economy, 30 I may cast integral with the preheating chamber 1, a series of arms or ribs 30, to form a grid for the support of utensils, irons, and other articles. The upper edges of these arms or ribs are spaced some distance 35 above the upper surface of the preheating chamber, and occupy the same plane as the upper edges of the transverse ribs or projections 31 of the conduit 15. Besides forming a grid, these arms or ribs constitute effective heat abstracting vanes for conducting heat to the preheating chamber.

When the burner is used as a regenerative gas burner, gas may be admitted to the preheating chamber by opening the valve 45 17. The gas accumulates and is diffused within said chamber and then passes downward through the conduit 4 into the burner chamber 2, from where it issues through the apertures 20. At this point it is mixed in 50 proper proportions, with the air that is drawn in through the bottom of the burner, the admission of the exact amount of air required to insure perfect combustion being governed by the adjustment of the shutter 6. 55 Now, when the burner is lighted, the products of combustion rise through the top of the burner, thoroughly heating the gas within the preheating chamber and affecting it as already described, the jets of gas issuing 60 from the inner series of burner apertures impinging against the center of the conduit 15, while those which issue from the outer series strike the bottom of the annular portion of the preheating chamber. I prefer to 65 make the wall 3 of the burner solid for by

so doing the combustion chamber will be protected against side drafts which it is believed might interfere somewhat with a perfect action of the burner.

When liquid fuel is used, it is turned in 70 through the diffusing and preheating chamber and flows down through the conduit 4, overflowing the burner chamber through the apertures thereof and flooding the trough 26. The valve is then closed and the fuel 75 lighted. The burning of this fuel heats the preheating chamber so that upon a subsequent opening of the valve, the fuel which passes through said chamber is vaporized and issues from the burner apertures in the 80 form of hydrocarbon gas. This now being lighted constantly heats the preheating chamber and makes the foregoing operation continuous so that the incoming liquid fuel is converted into gas before it is liberated 85 from the burner.

While I have shown and described the burner as circular, it is obvious that the shape may be varied without departing from the spirit of the invention. For instance, practically the same burner herein illustrated may be elongated to produce an oblong or elliptical burner; or the same may be rectangular in shape, as shown in Fig. 5. In said Fig. 5, the equivalents of the parts 90 of the previous form are referred to by the same reference numerals, augmented by the exponent "a".

Having thus described my invention, what I claim is:—

1. In a burner of the character described, the combination of a fuel diffusing and preheating chamber having an inlet and comprising a continuous passageway, a conduit connecting opposed portions of said chamber, a burner chamber located beneath the first mentioned chamber, a conduit communicatively connecting said first mentioned chamber and the burner chamber, a wall extending between the aforesaid chambers and inclosing a combustion chamber, the combustion chamber having an air admitting opening, the burner chamber having apertures, a trough supported adjacent the apertures of the burner chamber and into which the burner chamber may overflow, and means for controlling the supply of air to the combustion chamber.

2. In a burner of the character described, the combination of a fuel diffusing and preheating chamber having an inlet and comprising a continuous passageway, a cross conduit connecting opposed portions of said chamber, a burner chamber located beneath the first mentioned chamber and having a 125 series of apertures, a conduit communicatively connecting the first mentioned chamber and the burner chamber, a wall extending between said chambers and inclosing a combustion chamber, a wall extending down- 130

ward from the burner chamber thereby to provide an air inlet passageway, and means for controlling the supply of air through said passageway.

5 3. In a burner of the character described, the combination of a fuel diffusing and pre-heating chamber having an inlet and comprising a continuous passageway, a cross conduit connecting opposed portions of said 10 chamber, a burner chamber located beneath the first mentioned chamber, a conduit communicatively connecting the first mentioned chamber and the burner chamber, a wall extending between said chambers and inclosing 15 a combustion chamber, a wall extending downward from the burner chamber thereby to provide an air inlet passageway, means for controlling the supply of air through said passageway, the burner chamber having 20 a series of apertures, and a trough supported adjacent the apertures of the burner chamber and into which said chamber may overflow.

4. In a burner of the character described, 25 the combination of a fuel diffusing and pre-heating chamber having an inlet, a burner chamber located therebeneath, a conduit communicatively connecting said chambers, a wall extending between said chambers and 30 inclosing a combustion chamber, a wall extending downward from the burner chamber thereby to provide an air inlet passageway, means for controlling the supply of air through said passageway, the burner chamber 35 having a series of apertures, and a trough supported adjacent the apertures of the burner chamber and into which said chamber may overflow.

5. In a burner of the character described, 40 the combination of a fuel diffusing and pre-heating chamber having an inlet, a burner chamber located therebeneath and having a series of apertures, a conduit communicatively connecting said chambers, a 45 wall extending between said chambers and inclosing a combustion chamber, a wall extending downward from the burner chamber thereby to produce an air inlet passageway, and means for controlling the supply 50 of air through said passageway.

6. A burner of the character described comprising an annular preheating chamber having an inlet, an annular burner chamber located therebeneath and of less diameter 55 than the preheating chamber, a frusto conical wall connecting the outer sides of said chambers, a conduit through which communication is established between the preheating and burner chambers, a cylindrical 60 wall extending downward from the burner chamber thereby to provide an air inlet passageway, a circular wall extending across the lower end of said passageway, said wall being provided with air inlet openings, a shutter rotatably secured to said 65

wall and having openings that are adapted to coöperate with those of the wall, the burner chamber having apertures, and a ridge extending inward and upward from the burner chamber to provide a trough 70 into which the burner chamber is adapted to overflow.

7. A burner of the character described comprising an annular preheating chamber having an inlet, an annular burner 75 chamber located therebeneath and of less diameter than the preheating chamber, said burner chamber having apertures, a frusto conical wall connecting the outer sides of said chambers, a conduit through which communication is established between the preheating and burner chambers, a cylindrical wall extending downward from the burner chamber thereby to provide an air inlet 80 passageway, a circular wall extending across the lower end of said passageway, said wall being provided with air inlet openings, and a shutter rotatably secured to said wall and having openings that are adapted to coöperate with those of the wall. 90

8. A burner of the character described comprising an integral casting that is formed with an annular preheating chamber having an inlet extension, an annular burner chamber located therebeneath and of 95 less diameter than the preheating chamber, said burner chamber having apertures, a frusto conical wall connecting the outer sides of the aforesaid chambers, a conduit through which the preheating and burner 100 chambers communicate, a cylindrical wall depending from the burner chamber thereby to provide an air inlet passageway for the burner, a circular wall extending across the lower end of such passageway and having air inlet openings, and a shutter rotatably connected to such wall and having 105 openings that are adapted to be brought into register with the openings of the circular wall. 110

9. A burner of the character described comprising an integral casting that is formed with an annular preheating chamber, a conduit communicatively connecting diametrically opposed portions of the preheating chamber, said chamber having an inlet extension adjacent one end of said conduit, an annular burner chamber located beneath and of less diameter than the preheating chamber, a conduit communicatively connecting the preheating chamber adjacent the end of the aforesaid conduit remote from the inlet extension with the nearest portion of the burner chamber, the burner chamber having apertures, a ridge 115 extending inward and upward from the burner chamber thereby to form a trough into which the burner chamber is adapted to overflow through its apertures, a frusto conical wall connecting the outer sides of 120 125 130

the aforesaid chambers, a cylindrical wall extending downward from the burner chamber and inclosing an air inlet passageway, a circular wall extending across the bottom of said passageway and having air inlet openings, and a shutter rotatably connected to said wall and having openings that are adapted to be brought into register with the openings of said wall, certain of the 10 apertures of the burner chamber diverging to direct the jets of gas which issue therefrom against the annular preheating chamber, while others of the apertures converge to direct the jets issuing therefrom against 15 the first mentioned conduit.

10. A burner of the character described comprising an integral casting that is formed with an annular preheating chamber, a conduit communicatively connecting 20 diametrically opposed portions of the preheating chamber, said chamber having an inlet extension adjacent one end of said conduit, an annular burner chamber located beneath and of less diameter than the preheating chamber, a conduit communicatively connecting the preheating chamber 25

adjacent the end of the aforesaid conduit remote from the inlet extension with the nearest portion of the burner chamber, the burner chamber having apertures, a frusto 30 conical wall connecting the outer sides of the aforesaid chambers, a cylindrical wall extending downward from the burner chamber and inclosing an air inlet passageway, a circular wall extending across the bottom 35 of said passageway and having air inlet openings, and a shutter rotatably connected to said wall and having openings that are adapted to be brought into register with the openings of said wall, certain of the apertures of the burner chamber diverging to direct the jets of gas which issue therefrom against the annular preheating chamber, while others of the apertures converge to 40 direct the jets issuing therefrom against 45 the first mentioned conduit.

In testimony whereof I hereunto affix my signature in the presence of two witnesses.

ARCHIBALD R. THOMPSON.
